UNITED STATES PATENT OFFICE.

FRANK M. DUNN, OF OAKLAND, CALIFORNIA, ASSIGNOR TO UNITED STATES GLASS COMPANY, OF PITTSBURGH, PENNSYLVANIA, A CORPORATION OF PENNSYLVANIA.

DESIGN FOR AN ICE-CREAM GOBLET.

52,094.

Specification for Design.

Patented June 11, 1918.

Application filed February 18, 1918. Serial No. 218,002. Term of patent 7 years.

To all whom it may concern:

Be it known that I, FRANK M. DUNN, a citizen of the United States, and residing at Oakland, in the county of Alameda and State of California, have invented a certain new, original, and ornamental Design for an Ice-Cream Goblet, of which the following is a specification, reference being had to the accompanying drawing, forming a part

thereof, which is a view in perspective of the ice-cream goblet, illustrating my new design.

I claim:

The ornamental design for an ice cream goblet, substantially as shown.

FRANK M. DUNN.
